UNITED STATES PATENT OFFICE

2,209,604

COOLING DEVICE

Kenneth E. Lyman, Chicago, Ill., assignor to
 Borg-Warner Corporation, Chicago, Ill., a corporation of Illinois

Application November 12, 1936, Serial No. 110,456

3 Claims. (Cl. 62—91.5)

This invention relates to cooling devices employing solid, gas-emitting refrigerant such as solid carbon dioxide or the like.

It is an object of the invention to provide a cooling unit of this character which is simple, inexpensive, durable and quiet and economical in operation.

It is another object of the invention to provide an economical cooling unit employing a gas-emitting solid refrigerant.

A further object of the invention resides in the provision of a cooling device in combination with a suitable part of an automobile such as the luggage compartment without unduly obstructing the luggage space.

It is also an object of the invention to provide a cooling unit wherein the cooling medium also functions as insulation.

Another object of the invention resides in the provision of a cooling unit operated in such a manner as to substantially eliminate undesired insulation effect due to refrigerant.

It is a further object of the invention to provide means within ready reach of the driver or other person occupying the vehicle or other place in which the device in accordance with the invention is installed, for manual regulation and control of the rate of cooling.

The invention also contemplates the provision of an automatic control for the device.

Further objects and advantages of the invention will appear as the description proceeds.

The invention, in preferred forms, is illustrated in the accompanying drawings, in which:

Figure 1 is a vertical sectional view thru a cooling unit embodying the invention;

Figure 2 is a horizontal sectional view taken substantially as indicated by the line II—II in Figure 1;

Figure 3 is a broken vertical section-elevation taken substantially as indicated by the line III—III in Figure 1; and

Figure 4 is a view showing an automobile installation of a cooling unit in accordance with the invention.

Referring now particularly to the drawings, there is illustrated generally a cooling unit embodying the invention and adapted to be portable or of a permanently stationary character.

The unit may comprise a cabinet 1 with its side and bottom portions formed of metallic or other lining 2 and sheathing 3 between which thermal insulation 4 of any suitable character such as kapok is located.

A partition 5 forms with a side wall portion

of the lining a duct or chamber 7 communicating with the main chamber or compartment 8 through an opening 9 in the partition adjacent the bottom of the cabinet. Above the opening 9 there is preferably fixedly secured a grid or grille 10 of wire mesh or the like in the compartment 8. This grid is adapted to support one or more blocks 11 of dry ice such as solid carbon dioxide, or a quantity of such substance in the form of snow, for example, in a screen-like or other suitable container (not shown), which may be introduced through any suitable door 12 which may form a part of the cabinet. Such door will of course be suitably insulated as by having non-metallic contact with the remaining structure when the door is closed. To insure against complete covering of the grid, one or more inner-side wall portions and/or, if desired, the partition 5 may be formed with one or more open corrugations as shown at 13.

Gas produced by sublimation of the solid refrigerant courses down through the grid 10 and the opening 9 and up through the duct 7 which it leaves adjacent the upper part of the cabinet, where it enters a conduit 14 encased in suitable heat-insulation packing 15 covered by sheathing 17. At 16 the conduit affords an intake for a blower 19 operated by a suitable motor 20, all forming part of the superstructure 21. The motor may be driven by the power plant or other source of power in the car or other installation, a suitable switch (not shown) being also provided.

Between the top 22 and bottom 23 of the superstructure there is a partition 24, affording thereabove a duct 25 providing a discharge opening for the blower 19. Below the partition there is provided another conduit 26 which will be described in detail hereinafter. Suffice it to state at this point that no communication is permitted between the ducts 25 and 26, but communication between the duct 25 and the interior 8 of the cabinet is established by means of passages 25a extending transversely through and sealed from the conduit or duct 26.

It is accordingly apparent that provision is made for the complete cycling or excursion of the refrigerant gas. Any moisture that may collect, such as that resulting from entry of atmospheric air when the door is opened, may be discharged through a sump 27, suitably located, when the screw cap 27a is removed.

In accordance with the present invention, provision is made for a greatly increased air cooling effect over what has been the case heretofore.

To this end, the conduit or compartment 26 has air intake and discharge openings 28 and 29, respectively at its terminals. Air from the inlet 28 is acted upon by a blower 30 adjacent said inlet. The blower is mounted for rotation preferably by the motor 20 and discharges into the remainder of the conduit at 31. From the discharge space 31 and up to the conduit outlet 29, the conduit 26 constitutes a radiator core as at 32. The passages 25a extending through this core are preferably of oval cross section with the major axes parallel to the direction of air flow in the core, to offer reduced obstruction to the air flow and increased radiation between the air 15 and the refrigerant gas flowing thru said passages.

It will thus be seen that a forced draft and continuous flow of the refrigerant gas is afforded by the gas blower 19, and a like effect on the 20 air to be cooled is obtained by use of the air blower 30, and the large area of contact of the moving gas with the side walls and interior structure of the core 32 insures the transfer of adequate heat from the air to the gas flowing 25 through the passages 25a. In order to augment the heat transfer the wall 33 of the core 32 may be formed with relatively open corrugations so that the walls of each corrugation will be spaced apart sufficiently to obviate crowding and thus 30 will not interfere with the proper flow of the portion of the gas directly contacting the same.

In addition, it is pointed out that refrigerant gas has a relatively high insulating property. If the gas is allowed to move at a slow rate as, for 35 example, when it moves by convection, the friction of the confining wall with the gas forms a substantially stationary skin or layer of gas which serves as an insulating medium and substantially reduces the passage of heat from the air to 40 the gas. By running the gas at substantially increased velocity such as that obtained by a forced draft from the blower 19, the skin friction is overcome and the gas does not perform any insulating function and accordingly there is a substantially 45 greater passage of heat from the air to the gas. This is a matter of considerable importance when it is realized that carbon dioxide gas, for example, at or near the temperature of sublimation has about six times the insulating 50 value of cork.

It is to be appreciated that carbon dioxide gas is evolved from solid carbon dioxide, in an atmosphere of such gas, at about -109° F., and accordingly is capable of having a very great 55 cooling effect even though it may pass through the cooling cycle as many as twenty times, more or less, without reinforcement by cooler gas or contact with the solid refrigerant before a condition of thermal equilibrium between the gas 60 and the air occurs.

While the insulating material 4 may be of any character desired, it is preferably of cork, loose felt, wool, kapok or such other material as will 65 allow the gas to infiltrate and permeate the same and retain the gas. Accordingly, adjacent the top of the cabinet the lining 3 is pierced at 34 and the lining of the superstructure is pierced at 35 to allow the refrigerant gas to pass from the interior 8 of the cabinet and the passage 25 70 into the packing 4. When the packing is permeated with the gas, it has an insulating value which would be afforded by a wall of kapok or cork several times the thickness of the packing alone. This will be evident from the fact that 75 the gas has great insulating properties when at

rest, and it is in a condition of substantial rest when it permeates the insulating material.

A control valve at any suitable location as at the entrance of the conduit 14 as shown at 31 or in the conduit 14 as shown at 36, may be provided to regulate the rate of cooling afforded by the unit. Such a valve may be automatically controlled as by thermostatic means 38 influenced by the temperature of the gas from the chamber 8, or may be connected as by a Bowden wire to a 10 readily accessible point such as the dash of a car, as shown at 39, or other installation, for manual adjustment.

It will be observed that the unit is rather compact. One having an overall height and width 15 of about two feet and lateral depth of about one foot operates satisfactorily for automobiles in a wide range of body sizes and may be installed in a small space such as at one side of a luggage compartment as shown at 40, closed by a door 20 40a, where it is unobtrusive and will not materially encroach upon the space remaining available for luggage purposes.

The intake and discharge ends of the air conduit 26 may be located as conditions may require 25 or suggest. For example, in an automobile installation, it may be advantageous to position the intake at the deck 42 at one end of the rear seat 43, as shown in Fig. 4 at 44, the discharge end 45 leading to a tube 46 attached to or built 30 into the ceiling and extending forwardly to the middle or any other part of the body or may branch off as at 47 to discharge at the desired points. The discharge could be provided in a floor duct which could open at the floor board, 35 or in any other suitable part of the car.

The flow of gas is indicated by full line arrows as at 48 and the flow of air by dash line arrows as at 49.

The system, as stated, may be regulated to provide the desired degree of cooling. Investigations have shown that a differential of substantially 40 6° between the exterior and the interior of the confined space equipped with the cooling unit is preferred for the human system, since such 45 a differential provides the desired amount of comfort without deleterious physical effects. Differentials of 10° and 15° have been found undesirable because of the deleterious effects.

The invention is of course not limited in its 50 application to automobiles, since it is equally adaptable to trailers, rail cars and other forms of transportation, storage rooms, offices, habitations and in fact in any place where cooling is desired.

The unit need not necessarily have the shape 55 illustrated since it may be made substantially flat or in any other desired shape to be accommodated under the floor of the luggage compartment or in any other inobtrusive place.

The material forming the lining and casing of the cabinet and other sheet material parts need not necessarily be made of metal but if desired may be of non-metallic material such as composition and may be molded into the desired 65 shapes. It will be observed that the unit may be arranged conveniently with the cabinet door 12 readily accessible for replenishment of the cabinet as shown in Fig. 4.

I am aware that many changes may be made and numerous details of construction may be varied through a wide range without departing from the principles of this invention, and I therefore do not purpose limiting the patent granted 70 75

hereon otherwise than necessitated by the prior art.

I claim as my invention:

1. A cooling unit having an insulated fluid circuit adapted to contain gas-emanating refrigerant and two compartments separated by an up-standing wall open at its lower end to establish communication between the compartments, means providing forced draft for the gas in said circuit, an air radiator at the upper part of said wall and sealed from and dividing said circuit, and tubular means sealed from and passing through said radiator and establishing communication between the divided portions of said circuit.

2. In an air cooling system for utilizing solid CO_2 as the refrigerant, an insulated chamber having means to support a quantity of said refrigerant, an air conducting heat exchanger traversing said chamber, connections to said heat exchanger from the exterior of the chamber, for conducting air from a space to be conditioned, through said heat exchanger and back to said space, a blower for forcibly circulating the air through said connections and heat ex-

changer, a blower for forcibly circulating gaseous CO_2 sublimated from said refrigerant body, in contact with said radiator so as to overcome the tendency of said gaseous CO_2 to form an insulating layer in contact with the radiator and a motor common to both of said blowers, having a shaft on which said blowers are mounted.

3. An air cooling unit for a motor vehicle having a closed refrigerant gas circuit divided by an open air circulating radiator, the interior of which is sealed from said refrigerant circuit, said circuit having a passage traversing said radiator perpendicularly to the path of air flow therethrough to establish communication between the divided parts of the circuit and having a compartment adapted to hold a body of solid CO_2 refrigerant, and means providing forced draft for forcibly circulating the gaseous CO_2 in contact with said solid body of refrigerant and through said circuit so as to overcome the tendency of said gaseous CO_2 to form an insulating layer in contact with the walls of the radiator, and for forcibly circulating the air through said radiator.
